UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

THREAD-CUTTER FOR SEWING MACHINES.

Application filed December 17, 1921. Serial No. 523,056.

To all whom it may concern:

Be it known that I, EDWARD B. ALLEN, a citizen of the United States, residing at Newtown, in the county of Fairfield and State of Connecticut, have invented certain new and useful Improvements in Thread Cutters for Sewing Machines, of which the following is a specification, reference being had therein to the accompanying drawings.

This invention relates to sewing machines and particularly to buttonhole sewing machines having stitch-forming devices including needle and loop-taker mechanisms disposed mainly at opposite sides of the work; the loop-taker mechanism operating to detain a loop of needle-thread when the stitch-forming devices come to rest. One type of such machines also commonly embodies a rotary turret which carries the loop-taker or under thread mechanism and also carries the needle-throat or work-supporting button through which the needle reciprocates; the button being commonly apertured to guide a stay-cord to the stitch-forming mechanism in such wise that the stitches will be formed over the cord and bind the cord in its place around the buttonhole.

Machines of this character have heretofore been provided with thread and stay-cord severing devices operating automatically at the end of the sewing operation with the object of relieving the operator of the necessity for cutting the various threads by hand, and thereby shortening the time required by the operator to remove the stitched work from the machine and insert work to be stitched.

While prior thread-cutting devices may have operated satisfactorily in freeing the work from the sewing threads and thereby enabling the operator to shift or remove the work from the machine without delay, they have not operated to trim the threads, including the cord, with certainty and in such a manner that the buttonholes, as removed from the machine, were finished buttonholes that is, acceptable to the trade without being retrimmed by hand. While attempts have been made to provide buttonhole machines with thread-cutting devices for trimming the threads close enough to the buttonhole to avoid the necessity of a hand re-

trimming operation, such attempts have not been successful in meeting the demands of the trade, since the mechanisms heretofore produced have either failed to cut the thread clean and with certainty or have failed to cut the thread close enough to the buttonhole to produce an acceptable finished buttonhole.

For example, it has heretofore been proposed to mount a scissors device with its blades in parallelism with the work-supporting plates of the work-holder and between such plates and the work. In order to operate such a scissors device it is therefore necessary that the work-clamping feet be first raised to release the work prior to the projection of the scissors device to cutting position. The necessity for releasing the work before the threads are cut is disadvantageous in that the work is not held under control at the time the threads are cut and uniformly satisfactory results are impossible of attainment. An accidental disarrangement of the released work will have a tendency to affect the length of the trimmed threads or may even carry the threads beyond the range of action of the trimmer. There is also danger that the stitching will be cut and the work damaged.

Still, further, in prior machines having devices which operate to cut both limbs of the needle-loop detained by the loop-taker mechanism, difficulty is encountered for the reason that the short end of thread constituting the severed needle-loop is not taken care of and is frequently caught up by the stitch-forming devices and "sewed in," thus marring the product. An accumulation of such short ends on the turret may also interfere with the proper action of the under thread mechanism.

The present invention has for a primary object to provide a sewing machine, more particularly of the buttonhole type referred to, with thread-cutting mechanism of such a character that it will operate to trim the threads, including the cord, close to the work with certainty and uniformity, so that when the work is removed from the machine it will present a finished and acceptable appearance and will not need to be subsequently retrimmed by hand.

Another object of the invention is to provide means for taking care of the short ends

of thread constituting the severed needle-loops, so that they will not clog the stitch-forming mechanism or be sewed in.

A further object of the invention is to provide, in combination with the thread-cutting mechanism contemplated, means for holding the beginning end of the needle-thread, such means preferably operating in such a manner that the beginning end of the 10 needle-thread will be substantially concealed in the work.

Still further, the invention has for an object to provide means for insuring that the beginning end of the stay-cord will be 15 substantially even with the initial stitches so as to avoid the necessity of trimming the beginning end of the stay-cord.

In accordance with the present improvement, as embodied in a buttonhole sewing 20 machine, the above and other objects, as will hereinafter appear, are attained by mounting a thread-severing device below the level of the work-holder, and preferably independently of the turret, with its blade 25 or blades transverse to the plane of the work and so positioned as to engage and cut the threads, including the stay-cord, close to the last stitch, before the clamping feet are raised to release the work. Preferably, 30 the thread-severing implement is in the form of a scissors device, one of the blades of which is bluntly pointed and adapted to graze the under surface of the work exposed by an aperture in the work-support 35 and enter between such surface and the horizontally disposed threads leading from the aperture in the needle-throat or work-supporting button to the last stitch. The other blade is preferably mounted on the same 40 side of the first-mentioned blade as the last stitch in the work, in order that the threads may be cut very close to the end of the seam or buttohole.

The severed loop of needle-thread retained 45 by the loop-taker mechanism is removed from the field of action of the stitch-forming mechanism preferably by means of a movable thread-engaging device made up in the form of a gripper and mounted alongside 50 the thread-severing device so as to seize the severed needle-loop and carry it away from the stitch-forming mechanism when the thread-severing device is retracted. The thread-severing device and gripper are preferably operated simultaneously with the buttonhole-cutter by means of an operative connection receiving motion from the latter. Means are preferably provided above the work for nipping the needle-thread end 55 leading from the needle, so that the initial stitches may be formed without unthreading the needle. A pull-off may, in some cases, be provided to afford enough slack at the beginning of the sewing operation to permit 60 the needle to descend to the limit of its

stroke without unduly straining the needle-thread or pulling the thread out of the nipper. The beginning end of the needle-thread is preferably released by the nipper in time to take advantage of the thread absorbing action of the stitch-forming mechanism to draw down the beginning end of the needle-thread substantially flush with the work and thereby render such end practically invisible. 75

An auxiliary thread-cutter may also be associated above the work with the nipper in case it is desired to reduce the length of needle-thread end held by the nipper and thus reduce the length of thread end to be 80 absorbed or drawn back into the work by the stitch-forming mechanism. It is to be understood, however, that while the use of such auxiliary thread-cutter above the work is deemed preferable in the present 85 embodiment of the invention, it is not in all cases essential to the production of satisfactory work.

Inasmuch as it has been found impracticable to form the initial stitches flush with 90 the end of a short length of stay-cord projecting from the button, it is preferred to sever the cord at a sufficient distance from the button to afford a cord-end long enough 95 to be enclosed with certainty and bound down by the initial stitches, a cord-nipper being preferably provided to arrest the feed of the cord while the work and initial 100 stitches are slid toward the end of the cord, the cord being released when its end is even with the initial stitches.

An under thread pull-off is also preferably provided for the purpose of affording enough slack looper-thread so that the initial 105 stitches may be formed without unthreading the looper.

In the accompanying drawings, Fig. 1 is a right side elevation, partly in section, of a buttonhole sewing machine embodying the invention; the parts being in their respective positions occupied during the buttonhole cutting and thread-cutting operations. Fig. 2 is a left side elevation of the machine at the end of the buttonhole-producing cycle, the work-holder being open. Fig. 3 is a detail view of the guide-bracket for the needle-thread nipper releasing rod shown in Fig. 2. Fig. 4 is a detail sectional view of the needle-thread check shown in Fig. 2. Fig. 5 is a side elevation of certain parts of the needle-thread nipper thread mechanism shown in Fig. 2, the parts being in the respective positions which they occupy while the machine is sewing. Fig. 6 is a front elevation of the machine with the work-supporting plates in section. Fig. 7 is a fragmentary top plan view of the mechanism below the work-holder. Fig. 8 is a detail of the stay-cord nipper. Fig. 9 is a plan view of the work-support. 110 115 120 125 130

ing plate sections adjacent the sewing point. Fig. 10 is a bottom view of the needle-throat or button and the thread-cutting scissors and associated devices, the 5 scissors having advanced nearly to cutting position. Fig. 11 is a left side elevation of the needle-thread mechanism and associated parts at the point of the cycle when the initial stitches are being formed; the 10 dotted lines showing the movement of certain parts to open the nipper and release the beginning end of the needle-thread. Fig. 12 is a similar view of the parts at the end of the cycle when the 15 buttonhole is being cut and just after the thread-nipper has been tripped. Fig. 13 is a fragmentary plan view of the work-holder including the upper clamping feet and associated parts at the end of the sewing 20 operation but prior to the advance of the buttonhole-cutter. Fig. 14 is a sectional view on the line 14, 14, Fig. 13; the thread-nipper having been tripped. Fig. 15 is a perspective view of the scissors device, 25 thread-gripper, and associated parts, at the end of the sewing operation and prior to the advance of such parts. Fig. 16 is a similar view with the parts in advanced or cutting and gripping position. Fig. 17 is 30 a similar view showing the scissors and gripper being retracted to remove the severed needle-loop from the vicinity of the stitch-forming mechanism. Fig. 18 is a perspective view of the rear side of the 35 scissors device. Fig. 19 is a bottom perspective view of the needle-throat or button. Fig. 20 is a front elevation of the scissors device and associated parts, showing the connection with the lower button- 40 hole-cutter lever for tripping the latch which holds the needle-loop gripper open. Fig. 21 is an enlarged elevation of the scissor-blades showing one of them grazing the under surface of the work and entering 45 between such surface and the threads to be cut. Fig. 22 is a side elevation of the stay-cord nipper and looper-thread pull-off levers and their operating cam. Fig. 23 is a development of such cam. Fig. 24 is 50 a rear elevation of the actuating mechanism for the needle-thread nipper. Fig. 25 is a plan view of the timing cam member of such mechanism. Fig. 26 is a perspective view of such timing cam and its follower 55 in the respective positions which they occupy before the machine is started, as in Fig. 24. Fig. 27 is a similar view showing the cam-follower pin about to be elevated to open the needle-thread nipper. Fig. 28 is a similar view showing the cam-follower pin fully elevated and latched in ejected 60 position. Fig. 29 is a rear elevation of the same parts, the cam-follower pin having returned to its lower level. Figs. 30 and 31 65 are sectional views illustrating the opera-

tion of covering the beginning end of the stay-cord. Figs. 32 and 33 are front and reverse views, respectively, of the finished buttonhole as produced by the machine:

For the purpose of the present disclosure 70 the invention is embodied in a sewing machine of the buttonhole type constructed substantially in accordance with the disclosure of my United States Patent No. 15,324 reissued April 4, 1922. A machine 75 of this type, as shown particularly in Fig. 1, comprises a frame including a hollow box-like bed 1 from one end of which rises the standard 2 carrying the bracket-arm 3 which terminates in the needle-bar carrying head 4. The stitch-forming mechanism is constructed substantially in accordance with the disclosure of my Patent No. 1,372, 80 473 of March 22, 1921, and comprises the laterally vibrating needle 5 and the usual loop-taker or under thread mechanism mounted on the rotary turret 6 and including the threaded looper 7, non-threaded looper 8 and their respective loop-detainers 9 and 10. The turret 6 also carries the needle-throat or button 11 which is formed with the usual needle-aperture 12 and guide-way for the stay-cord c. The needle-thread is shaded and the looper-thread is 85 shown clear, or without shading, in the various figures.

The stitch-forming mechanism is operated from the sewing shaft 12 at the rear end of which is the usual belt-pulley 13 and stop-motion device which is constructed substantially in accordance with the disclosure of my said reissued Patent No. 15,324, and includes the tilting stop-motion lever 14 which is pivoted at 15 and carries the stopping tooth 16 adapted for cooperation in a manner well known with the stopping cam 17.

Within the bed 1 is mounted the usual feed-wheel 18 which is driven during the sewing by a suitable one-way gear-driven connection with the upright shaft 19 driven by the bevel-gear connection 20, 21 with the sewing shaft 12, as shown in my said reissued patent. The feed-wheel is connected to be driven at a higher speed both prior and subsequent to sewing by the usual automatically operated clutch (not shown) intermediate the constantly running shaft 22 and the rapid feed-shaft 23 which latter is permanently geared at 23' to the feed-wheel 18.

The work-holder which has the usual operative connections with the feed-wheel, comprises the lower work-supporting plates 24 and the upper pivotally mounted clamping feet 25 sustained by the respective clamping levers 26, Fig. 2, pivoted at 27. The clamp is closed in the usual manner either by rearward pressure against the finger-piece 28 or downward pressure on the arm 29 fixed to the clamp-closing rock-shaft 125 130 135 140 145 150 155 160 165 170 175 180

30. The clamp is usually closed automatically at the beginning of the sewing operation by the action of the usual three-armed rock-lever 31, 32, 32' having a roll 33 at the 5 forward end of the arm 31 adapted to depress the arm 29; the free end of the arm 32 carrying a slide-bolt 34 adapted for temporary engagement with the cam-groove 35 in the inner face of the continuously rotat- 10 ing pulley 36 which is loose on the button-hole cutter shaft 37, all as more fully explained in my said reissued Patent No. 15,324.

It is understood by those skilled in the art 15 that when a machine of this type is not in operation, the pulleys 13 and 36 are running freely on their respective shafts 12 and 37; the pulley 13 being geared at 38, Fig. 1, to the shaft 22 so as to drive the latter con- 20 stantly. When the machine is started, the bolt or slide-pin 34 is released and allowed to enter the cam-groove 35 in the pulley 36, whereupon the three-armed rock-lever receives one complete oscillation, serving in 25 its initial movement to close the clamps and in its return movement to spread the latter. The rock-lever also operates during its return movement through connections (not shown) with the arm 32' to effect the cou- 30 pling of the feed-wheel 18 and rapid feed-shaft 23 to the rapid drive shaft 22 where- upon the work-holder is rapidly shifted forwardly from cutting position to sewing position. When the work-holder reaches sewing 35 position the rapid drive-shaft 22 is un- clutched from the rapid feed-shaft 23 and feed-wheel 18, and the stitch-forming mecha- 40 nism is started, whereupon the feed-wheel and rapid feed-shaft 23 are more slowly driven through the usual gear connections with the sewing shaft and the work is moved in the usual path to space the stitches around the buttonhole. When the sewing is completed the stop-motion lever 14 is tri- 45 ped to stop the sewing shaft 12 and the rapid feed-shaft 23 and feed-wheel 18 are again connected to the rapid drive-shaft 22 which operates to rapidly shift the work- 50 holder rearwardly from sewing to cutting position.

Upon arrival of the work-holder at cutting position the pulley 36 is connected for a single rotation to the cutter-shaft 37 carrying the usual cutter advancing and retract- 55 ing cam 39 and the cutter closing cams 40, 41 which the latter operate to rock their respective upper and lower cutter-levers 42, 43 upon their common fulcrum 44 sustained by the usual travelling fulcrum-block 45, 60 Fig. 7, mounted in the slide-ways 46 in the bed 1. The fulcrum-block 45 has rigid with it a rearwardly extending arm 47, Fig. 1, which is connected by the usual link 48 and cam-follower 49 to the cam 39, it being un- 65 derstood that the fulcrum-block 45 is first ad-

vanced to carry the cutter-levers bodily forward to cutting position, whereupon the cams 40 and 41 close the cutter-levers upon the work, as indicated in dotted lines in Fig. 1.

After the buttonhole has been cut and during the retracting movement of the button-hole cutter levers, a cam 50, Fig. 2, on the cutter-shaft rocks a bellcrank-lever 51 connected to the push-rod 52 which engages 70 the then upright arm 53 on the clamp-closing rock-shaft 30 and pushes such arm forwardly to the position shown in Fig. 2, thereby effecting the raising of the clamping feet and the release of the work.

It is well known that the needle-throat or button of a machine of the type under consideration supports the portion of the work immediately adjacent the sewing point and is adapted to guide a stay-cord to the stitch-forming mechanism so that the stitches will be formed over the stay-cord and bind the latter in position around the buttonhole. Also, it is known that when the stitch-forming mechanism of a machine 80 of the type under consideration is stopped, a loop of needle thread is retained by the loop-taker mechanism. Consequently, when the work is shifted rearwardly from sewing to cutting position, there are four thread 85 lengths leading from the needle-hole in the button to the last stitch. One of these threads is the stay-cord. Another is the under or looper-thread. The remaining two are the limbs of the detained needle-loop. 90

Thread-cutter.

In accordance with the present improvement these threads are not only severed to permit ready removal of the work and facilitate restarting of the machine, but they are severed very close to the last stitch before the work-holder is opened, whereby certainty and uniformity of operation is attained and the work acceptably finished before it leaves 100 the machine; subsequent retrimming operations being unnecessary.

The thread-cutting mechanism comprises a thread-severing implement preferably in the form of a scissors device, Figs. 17 and 18, 115 and including the ledger-blade 51 and cutter-blade 52 pivotally mounted on the screw-pin 53 threaded into the thread-cutter carrier 54. A spring-washer 55 beneath the head of the screw 53 maintains the scissor-blades in operative contact with one another. The ledger-blade 51 is pointed at its upper end and at its lower end is slotted at 51' to admit the screw 55 threaded into the carrier 54. The screw 55 and slot 51' permit 120 adjustment of the blade 51 about the pivot 53 to raise or lower the path of movement of its pointed extremity so that the latter will properly graze the under surface of the work without digging into the latter. It 125 130

may be here explained that the point of the ledger-blade is not sharpened like a needle-point but is somewhat dulled or rounded so that it will not catch the fibers of the work.

5 The scissors-carrier 54 is preferably formed with a foot 56 having a rib-and-groove connection 56' with the rearward extension 57 of the scissors-support 58 which is preferably in the form of a lever pivoted 10 on the horizontal screw-pin 59, Fig. 6, sustained by the turret casing or curb 60. The screw 61, Fig. 7, which secures the scissors-carrier to the lever 58, passes through a slot 62 in the foot 56 and permits adjustment 15 of the scissors-carrier lengthwise of the buttonhole or, in other words, lengthwise of the direction of movement of the work-holder from sewing to cutting position; this adjustment determining the distance from 20 the end of the buttonhole at which the threads are cut. The axis of the pivot-screw 59 is directly below and substantially in intersecting relation with a line normal to the work at the sewing point. When the lever 58 is rocked, the point of the ledger-blade is caused to graze the under surface of the work which is substantially tangent to the path of movement of such point.

25 Mounted on the lever 58 by means of the rib-and-groove connection 63, Fig. 7, and the screw-and-slot expedient 64, Fig. 6, for adjustment, is a block 65 carrying the pin extension 66 which enters an aperture in the connection block 67 having a second aperture at right angles to and in non-intersecting relation with the first-mentioned aperture. Received within the second-mentioned aperture is the pin extension 68 of a horizontal arm 69 of a bellcrank-lever 30 pivoted at 70 to the bracket 71 mounted on the turret casing 60. The upright arm 72 of the bellcrank-lever is connected by means of the bent link 73 to the cutter-lever fulcrum-pin 44. Thus, when the cutter-levers are advanced at the close of the buttonhole-producing cycle, preparatory to cutting the buttonhole, the scissors carrier lever 58 is 35 rocked about its fulcrum 59 to advance the scissors from their retracted or inactive position, Fig. 15, to cutting position, Figs. 16 and 20, during which movement the point of the ledger-blade passes between the under surface of the work and the threads leading from the last stitch to the needle-throat, as 40 shown in Figs. 10, 14 and 21.

45 The work-supporting plates 24, Fig. 9, are formed with the usual clearance slot 24^a for the work-supporting button 11 and are further formed with the clearance slot 24^b for the thread cutter blade 51. The slot 24^b is transverse to the slot 24^a and is spaced from the button 11 when the work-supporting plates 24 are in buttonhole cutting position, as shown in Figs. 9 and 10.

50 The cutter-blade 52 of the scissors has

fixed thereto a lateral pin 74 which enters a cam-groove 75 in a stationary cam-block 76 fixed to the bed 1. This cam groove 75 is concentric with the pivot-screw 59 throughout the major portion of its length to hold 55 the scissors open, but at its upper end 77 is extended inwardly toward the axis of the pivot 59 to depress the pin 74 and thereby move the blade 52 to cut the threads. The planes of the scissor-blades are transverse 75 to the plane of the work and are between the needle-throat 11 and the clamping feet 25, whereby such blades may be readily advanced to seize and sever both limbs of the detained needle-loop, the looper-thread and 80 the stay-cord which lie lengthwise of the slot 24^a and across the slot 24^b.

Needle loop removing means.

85 The means for removing the severed needle-thread loop from the vicinity of the stitch-forming implements preferably comprises a gripper having the relatively separable jaws 78, 79. The jaw 78 is formed as an extension of the plate 80 which is secured to the front side of the scissors-carrier 54. The plate 80 is formed with the spaced ears 81 between which is pivoted at 82 the jaw-lever 83 at the free end of which is the 90 jaw 79.

95 The jaw-lever 83 is backed by a spring 84 which urges the jaw 79 toward the jaw 78, and is also formed with an angular extension 85 which is adapted when the jaws 78, 79 are opened, to be engaged by the latch-arm 86 and hold the jaws open, as shown in 100 Fig. 15. The latch-arm 86 is fixed to one end of the fulcrum-pin 87 which is journaled in the carrier 54 and carries at its other end an arm 88 having a bent extremity 89 adapted to be lifted to release the gripper jaw-lever 83 by the upward movement of the lateral pin 90, Fig. 16 and 20, fixed to the 105 lower cutter-lever 43.

110 The gripper-jaw lever 83 is also formed with a bent arm 91 which is adapted, when the scissors carrier is retracted, to strike the stop 92 and open the gripper-jaws to release the severed needle-loop. The spring 93 surrounding the pin 87 serves to re-set the latch 86 in the position shown in Fig. 15 to hold the gripper-jaws open during their next advance to loop-seizing position. When the gripper-jaws are advanced to loop-seizing 115 position and the latch 86 is tripped by the upward movement of the lower button-hole cutter lever, the jaws 78, 79, seize the severed needle-thread loop *n*, as shown in Fig. 16. The severed needle-loop is removed 120 from the vicinity of the stitch-forming instrumentalities during the subsequent retraction of the gripper, as shown in Fig. 17.

Stay-cord nipper.

125 In order to prevent accidental unthread-

ing of the stay-cord *c* from its guideway in the button 11, the latter may be provided at its under side intermediate the cord-guiding apertures 94 with a check in the form 5 of a light spring 95, Fig. 19.

- The stay-cord is led from the supply through the tube 96, Fig. 22, and check 97; thence between the nipper-jaw 98 and the adjacent vertical wall of the bed 1; thence 10 through the guides 99, 99' and 99'', Fig. 7, to the button 11. The nipper-jaw 98, Fig. 8, is in the form of a plate which is supported by the two screws 98', loosely received in the apertured end of the nipper-lever 100. 15 At its center the plate 98 is backed by the adjustable screw 101 to vary the grip of the plate 98 upon the cord. The lever 100, Fig. 22, is fulcrumed upon the screw 102 which enters the bracket 102' on the bed 1. 20 At its rear end the lever 100 carries a cam-roll 103 which is actuated by the outer face cam 104 on the disk 105 fixed to the rapid feed shaft 23. The spring 106, Fig. 7, tends to rock the lever 100 to release the cord. 25 The cam 104 is timed to cause the plate 98 to grip the cord as soon as the machine is started and hold the cord during the formation of the initial stitches, Figs. 30 and 31, so that the initial stitches will be slid along 30 by the initial feed of the work to a position even with the end of the cord, Fig. 31, whereupon the cord is released and allowed to feed with the buttonhole.

Looper thread pull-off.

- 35 A looper-thread pull-off is preferably provided for the purpose of affording slack looper-thread at the completion of the stitching, so that the looper-thread will not be 40 under strain when it is severed and so that the end of the looper-thread will not be pulled back through the button 11 at the beginning of the next sewing operation. Pivoted on the screw 107, Fig. 6, is the pull-off lever 108 at the lower end of which is the hook 109 which engages the looper-thread between the tension device 110 and the stationary thread-guide 111. The lever 108 is connected at its upper end to a link-bar 112 which passes freely through an aperture in the side wall of the bed 1 and at its outer grooved end is embraced by the forward forked extremity 113, Fig. 22, of the lever 114 fulcrumed on the screw 102 and at its 50 rearward end, Fig. 7, carrying a roll 115 adapted to be actuated by the cam 116 on the inner face of the cam-disk 105. The cam 116 is timed to give the pull-off lever one complete oscillation from full to dotted line 55 position and return, Fig. 6, when the sewing operation has been completed and at about the time the rapid feed is thrown into action to shift the work to cutting position. A spring 117 on the bar 112 between the collar 60 118 and the bed 1 operates to restore the pull-off lever 108 to its full line position.

Needle-thread nipper.

To avoid a possible accidental unthreading of the needle and to facilitate the starting of the sewing operation, an upper thread-controlling element is preferably provided to act upon the needle-thread length between the needle-eye and the work. Such element is preferably in the form of a thread-nipper operating at the end of the sewing operation to catch the needle-thread before it is severed below the work and hold such thread during the formation of the initial stitches; means being preferably provided to cause the nipper to release the end of the needle-thread in time for such thread to be drawn down to an inconspicuous or substantially invisible position by the pull or thread-absorbing action of the stitch-forming instrumentalities. An auxiliary thread-cutter may, if desired, be associated above the work with the needle-thread nipper to somewhat reduce the length of needle-thread end to be absorbed or drawn back into the work during the formation of the initial stitches.

In the accompanying drawings there is disclosed an upper thread-nipper having an auxiliary thread-cutter associated therewith. These elements are in the form of the usual compound blade 119, Figs. 13 and 14, which is mounted on the pivot-pin 120 journaled in the left-hand work-clamping foot 25 and operates between the upper and lower resilient arms 121, 122, in the usual manner as disclosed, for example, in my Patent No. 1,369,371, of February 22, 1921. The compound blade 119 has a hook-shaped extremity which swings across the lead of the needle-thread at the end of the sewing operation, catching such thread and nipping it between the resilient arms 121, 122. If, as in the particular construction disclosed, the blade 119 has a sharpened lower corner 123 and the lower resilient arm 122 is sharpened or fitted with a ledger-blade 124, the needle-thread will be severed as well as nipped above the work, as illustrated in Fig. 14.

The mechanism for operating the nipper-blade 119 is similar in its principle of operation to that disclosed in my said Patent No. 1,369,371. In the present instance the pivot-pin 120 carries the usual crank-arm 125 to which is pivotally connected at 126 the forward end of the link 127 pivotally connected at its rearward end at 128 to the lower end of the lever-plate 129. The lever-plate 129 is pivoted at 130 to a bracket-plate 131 secured by screws 132, Fig. 12, to the inner face of the usual fulcrum block in which the upper work-clamping arm 26 is pivoted.

A coil spring 133 connected at its opposite ends, respectively, to the bracket-plate 131 and lever-plate 129 serves to draw the link 127 rearwardly and shift the blade 119 to nipping position, Figs. 12 and 14. A stop 134 mounted on the bracket-plate 131 limits the motion of the lever-plate 129 under the influence of the spring 133.

The lever-plate 129 is formed with a laterally extending arm 135 which is positioned in the path of downward movement of the horizontally and forwardly extended lower end 136 of the vertical nipper opening rod 137. The lever-plate 129 is also formed with a forwardly extended tooth 138 under which snaps the lateral tooth 139 of the latch-plate 140 pivoted at 141 to the bracket-plate 131. A spring 142 connected at its opposite ends, respectively, to the latch-plate 140 and bracket-plate 131 yieldingly holds the plate 140 in latching or dotted line position, Fig. 11. The latch-plate 140 is fitted at its lower end with an adjusting screw 143, Fig. 13, the free end of which is directed toward the fulcrum-pin 44 of the buttonhole cutter-levers and is in position to be struck and displaced forwardly to release the lever-plate 129 by the vertical wall portion 144, Fig. 13, of the upper cutter-lever 42, when the buttonhole cutter levers are advanced to cutting position at the end of the sewing operation.

The release of the needle-thread end at the proper time is secured by connecting the rod 137 with a timing cam 145 which is mounted on the vertical shaft 146 journaled in the bracket-arm 3 in alinement with the shaft 19 and driven by a two-to-one speed reducing bevel-gear connection 147 with the needle-bar operating shaft 148, which is driven in the usual manner by the one-to-two speed multiplying bevel-gear connection 149 to the shaft 19. The rod 137 is pivotally connected at its upper end 150 to the forward end of the lever 151 and is guided in its movement by being passed through an aperture in a guide-bracket 152, Figs. 2 and 3, fixed to the fulcrum-pin 153 of the usual bellcrank gear-segment 154 which is commonly used in machines of the present type to turn the needle-bar mechanism in synchronism with the turret in sewing around the eye of the button-hole.

The lever 151 is pivoted at 155 to the bracket arm 3 and at its rearward end is pivotally connected at 156 to the lower end of the link 157, Fig. 24, which is apertured at its upper end to fit the reduced end 158, Fig. 25, of the boss 159 formed at the lower end of the slide-plate 160 having its opposite edges longitudinally grooved at 161 to slidably fit the opposed vertical ribs 162 afforded by cutting away the wall of the

housing 163 which incloses the timing cam 145.

It will be clear that an up-and-down motion of the slide-plate 160 along its ways 162 will rock the lever 151 and set the needle-thread nipper in open position; the latch 140 operating to hold the nipper open. A spring 164, Fig. 2, connected at its opposite ends, respectively, to the lever 151 and standard 2 restores the rod 137 to its elevated position and the slide-plate 160 to its lowermost position.

The boss 159 on the slide-plate 160 is apertured to receive the slide-pin 165 which is adapted, when released, to be projected toward the timing cam 145 by the leaf-spring 166 mounted on the link 157. The slide-pin is formed with a circumferential groove 167 which is adapted to be entered by the lower end-portion of a latch-lever 168 pivotally mounted at 168' on the slide-plate 160. The latch 168 acts during the major portion of the sewing operation to hold the slide-pin 165 in ejected position and out of engagement with the active portions of the timing cam 145, as shown in Fig. 29. When the sewing is completed, however, and the stop-motion lever 14 springs to stopping position, Figs. 1 and 2, the characteristic up-and-down motion of the stopping tooth 16 operates in a well known manner, as explained in my said reissued Patent No. 15,324 to rock the lever 169 and cause the pin 170 to engage under the latch 171 and lift the tension release bar 172. In the present instance the bar 172 is formed at its upper end with a wedge 173, Fig. 24, which cooperates with the tension release pin 174 to separate the disks of the tension device 175.

The bar 172 carries a lateral pin 176 which lifts the tail 177 of the latch-lever 168 against the pressure of the spring 178 and releases the slide-pin 165, whereupon the latter is projected into engagement with the then stationary cam 145 by the spring 166, as shown in Figs. 24, 25 and 26.

When the stitch-forming mechanism is again started, the tension release bar lifting pin 170, Fig. 2, is carried inwardly beyond the latch 171 and the tension-release pin 172 drops into the position shown in Fig. 5, thus restoring the tension on the needle-thread. The cam 145 is provided with a lower circular ledge 179 and a cam-rise 180 leading to the ledge 180' which in the initial movement of the stitch-forming mechanism passes under the inner end of the slide-pin 165 and lifts the latter enough to depress the extension 136 of the rod 137 substantially into engagement with the extension 135 of the lever-plate 129. In other words, the rise 180 initially lifts the slide-plate 160 sufficiently to take up the lost-motion in the

train of connections with the latch-plate 129. At the end of the ledge 180' is a cam-
rise 181, Fig. 27, leading to a second ledge 182 which lifts the plate 160 sufficiently to
5 rock the lever 129 and set the needle-thread
nipper in open position. The rise 181 is
preferably timed to effect the release of the
needle-thread end at about the time the
needle-bar completes the up-stroke follow-
10 ing the first descent of the needle through
the work. Further movement of the cam
145 carries the cam incline 183 into engage-
ment with the inner end of the pin 165
whereupon such pin is ejected and latched by
15 the lever 168, as shown in Fig. 28. The
ledge 182 subsequently rides from under the
pin 165 and permits the latter to drop to its
initial position upon the lowermost ledge
179 where it rides idly during the balance
20 of the sewing operation, as shown in Fig. 29.

The needle-thread passes from the supply
through the guide-tube 184 and light thread-
check 185; thence between the tension-disks
175 and through the guide-aperture 186,
25 Fig. 25, in the wall of the cam housing 163.
The needle-thread next passes through the eye
187 at the end of the check-spring 188; thence
through the guides 189, 190, and under the pull-off bar 191, Fig. 2; which at
30 its lower end is connected to the clamp-clos-
ing lever 31 and operates prior to sewing,
as indicated in Fig. 2, to pull enough needle-
thread through the then open tension 175 to
permit the needle to reach the bottom of its
35 stroke, in its initial descent, without unduly
straining the needle-thread. From the pull-
off 191 the needle-thread passes through the
guide 192 and under the guide-bar 193; thence
40 into the hollow needle-bar 194 and
to the needle 5.

The thread-check 185 preferably comprises
a cylindrical body 195, Fig. 4, apertured to
receive the spring 196 and movable disk
197. The upper disk 198 is carried at the
45 upper end of the pin 199 fixed in the sup-
port 195 by the set-screw 200. The pin 199
is apertured at 201 to guide the needle-thread
between the disks. The purpose of the
thread-check 185 is to apply a light resis-
50 tance to the needle-thread so that during the
action of the pull-off 191 and when the main
tension 175 is opened, overrunning of the
needle-thread will be prevented.

55

Operation.

When the machine is ready to start, Fig.
2, the work-clamping feet are in raised pos-
ition; the main tension 175 is open and the
55 plunger-pin 165 is in engagement with the
cam 145, as shown in Figs. 24 and 25. The
end of the needle-thread is held by the nip-
per 119, 121. The looper-thread and cord
are sticking up through the aperture in the
60 button 11 and the looper-thread is in a slack

condition due to the operation of the looper-
thread pull-off at the close of the previous
cycle of operations. The stay-cord nipper
is open.

When the machine is started, the three-
70 armed lever 31, 32, 32' is rocked to close the
work-clamp and operate the needle-thread
pull-off 191. In its return movement, the
arm 32' of the three-armed lever operates
75 as usual to spread the work-clamp and trip
the rapid feed into action to quickly shift
the work-holder forwardly from cutting
position, Figs. 12 and 13, to sewing position,
Fig. 11. At the beginning of the rapid
80 feed motion, the cam 104 closes the stay-
cord nipper 98 and as the work slides for-
wardly over the button 11, the end of the
stay-cord *c* if bent sidewise or rearwardly
85 during the insertion of the work, is brushed
back into line with the buttonhole, as shown
in Fig. 30, so that it will be embraced by the
initial stitches.

When the work reaches sewing position
the rapid feed mechanism is thrown out of
action and the stop-motion lever 14 is tilted
90 to start the stitch-forming mechanism. At
about the end of the up-stroke of the needle
following its initial descent, the cam 145
operates to release the end of needle-thread
held by the nipper 119, 121, whereupon such
95 end is absorbed or drawn back into the work
by the action of the stitch-forming instru-
mentalities in substantially the manner dis-
closed in my said Patent No. 1,369,371.
When the work has been fed sufficiently to
100 slide the initial stitches even with the end of
the stay-cord, Fig. 31, the cam 104 passes be-
yond the follower 103 and releases the stay-
cord so that the latter will feed with the
buttonhole. The beginning end of the seam
105 thus presents a finished appearance and the
sewing proceeds in the usual manner around
the buttonhole.

When the sewing is completed, the stop-
110 motion lever 14 is tripped and arrests the
action of the stitch-forming mechanism, at
the same time releasing the tension 175 and
plunger-pin 165, as previously described.
The rapid feed is again thrown into action
115 and quickly carries the clamped and stitched
work to cutting position, thereby drawing
out the looper-thread, stay-cord *c*, and both
limbs of the detained needle-loop *n* from the
aperture in the button 11, as shown
120 in Fig. 15, and positioning these threads
horizontally across the path of advance of
the scissors device 51, 52.

Upon the arrival of the work at cutting
position, the cutter-shaft 37 is coupled as
125 usual to the pulley 36 for a single rotation
and operates to advance the buttonhole cut-
ter levers 42 and 43 to cutting position and
to close them upon the work. The advance
movement of the buttonhole cutter levers
130 also effects the advance of the scissors de-

vice and needle-loop gripper to their operative position, Fig. 16.

The screw 143 is preferably so adjusted as to effect the tripping of the needle-loop nipper before the scissors device severs the lower threads.

When, as in the present instance, the needle-thread is cut above the work, the wedging action of the point of the ledger-blade 51 of the scissors device, in passing between the threads and the under surface of the work, exerts a pull on the threads and draws down the needle-thread end before the lower threads are severed. When the cutter-levers 42, 43 recede, the scissors device is retracted and the needle-loop nipper recedes, Fig. 17, carrying with it the detained needle-loop 71 both limbs of which were severed by the action of the scissors, as shown in Fig. 16. As the scissors-carrier nears its retracted position, the stop 92 is struck by the arm 91 of the nipper-jaw 79 and the latter is opened, thus releasing the severed needle-loop 71 just prior to the final stoppage of the machine.

Thus the buttonholes *b*, Figs. 32 and 33, when removed from the machine, are entirely finished; the cord *c* and sewing threads being neatly trimmed at the point *d* close to the end of the buttonhole. Moreover, this result is attained with certainty since the work is held in position by the work-clamp until the threads are actually cut.

While the invention is disclosed as embodied in a buttonhole sewing machine, its field of usefulness in its broader aspects, embraces sewing machines generally, as will be obvious to those skilled in the art without further discussion.

Having thus set forth the nature of the invention, what I claim herein is—

1. A sewing machine including stitch-forming mechanism, an apertured work-support, a thread-cutter including a pointed blade disposed transverse to the work-support, and means for projecting the point of said blade into said aperture but not appreciably above the upper surface of the work-support so as to graze the under surface of the work.

2. A sewing machine including stitch-forming mechanism, an apertured work-support, a scissors thread-cutter having its blades disposed below the work-support and in planes transverse to the work-support and means for projecting said thread-cutter into said aperture but not appreciably above the upper surface of said work-support.

3. In a sewing machine in which that portion of the thread to be cut lies substantially parallel to and in contact with the surface of the work, a thread-cutter including a blade disposed transverse to the surface of the work and having a pointed

extremity, and means for moving said thread-cutter transversely of the lead of the thread and in a path such that the extremity of said blade will graze the surface of the work and enter between such surface and the thread to be cut.

4. In a sewing machine, in which that portion of the thread to be cut lies substantially parallel to and in contact with the surface of the work, a thread-cutter including a blade having a pointed extremity, said thread-cutter being pivotally mounted so as to direct the movement of the pointed extremity of said blade in a curved path grazing the surface of the work crosswise of the lead of the thread in a plane transverse to the surface of the work, whereby such blade will enter between the surface of the work and the thread to be cut preparatory to the cutting action.

5. A sewing machine having, in combination, stitch-forming mechanism including a needle, a needle-throat, a work-clamp, automatic clamp-opening means, a thread-cutting element below the work-clamp, and automatic means for moving said element before the work-clamp is opened to engage and sever the thread or threads at a point intermediate the needle-throat and the last stitch.

6. In a sewing machine in which the work is held in a work-clamp and that portion of the thread to be cut lies substantially parallel to and in contact with the under surface of the work, a thread-cutter including a blade disposed below the work-clamp in a plane transverse to the work and having a pointed extremity, and means for moving said thread-cutter transversely of the lead of the thread while the work-clamp is closed, to cause the extremity of said blade to enter between the surface of the work and the thread and sever the thread.

7. A sewing machine having, in combination, stitch-forming mechanism including needle and loop-taking devices, means including a needle-throat for sustaining the work against the thrust of the needle, a thread-cutter mounted below the work to operate in a plane transverse to the plane of the work, and means for moving said thread-cutter to cause the latter to graze the under surface of the work and sever the thread drawn out from the needle-throat.

8. A sewing machine having, in combination, stitch-forming mechanism including a reciprocating needle and complemental loop-taking means, a work-support, a thread-cutter including a blade having a cutting edge and a pointed extremity, said thread-cutter being mounted to move in a curved path transverse to the plane of the work so that the pointed extremity of said blade will graze the surface of the work transversely of the lead of the thread and separate from

such surface the thread to be cut, and means for moving the thread-cutter in the prescribed path.

9. A sewing machine having, in combination, stitch-forming mechanism including a reciprocating needle and complementary loop-taking means, a work-support, a thread-cutter mounted below the work-support and including a blade having a cutting edge and a pointed extremity, said

10 thread-cutter being mounted to move in a path such that the pointed extremity of said blade will graze the under surface of the work and separate from such surface

15 the thread to be cut, and means for moving the thread-cutter in the prescribed path.

10. A sewing machine having, in combination, stitch-forming mechanism includ-

20 ing a reciprocating needle and complementary loop-taking means, a work-support, a thread-cutter pivotally mounted below the work-support to operate in a plane trans-

25 verse to the plane of the work, said thread-cutter including a blade having a cutting edge and a pointed extremity, the curved path of movement of which grazes the under surface of the work at the highest point of such path, and means for operating

30 said thread-cutter.

11. A sewing machine including a recip-

35 rocating needle and complementary loop-tak-

ing means, a work-support, a thread-cutter in the form of a travelling scissors device and including a blade having a cutting edge

40 and a pointed extremity, said scissors de-

vice being disposed edgewise relative to the

work and being mounted to move in a path

such that the pointed extremity of said

blade will graze the surface of the work and

enter between such surface and the thread

to be cut, and means for moving the thread-

45 cutter in the prescribed path.

12. A sewing machine having stitch-form-

45 ing mechanism, a needle-throat, a work-hold-

er having a lower work-supporting surface

and formed with a thread-cutter clearance

aperture exposing the under surface of the

work, and a thread-cutter mounted below

the work-holder and adapted to engage the

50 under surface of the work exposed by said

aperture and sever the thread drawn out

from the needle-throat.

13. In a buttonhole sewing machine,

55 stitch-forming mechanism including a recip-

rocating needle and a needle throat mem-

ber, a work-clamp having lower work-sup-

porting and upper clamping means, the

work-supporting means being formed with

60 an elongated clearance slot for the needle-

throat member, said work-supporting means

being also formed with a thread-cutter clear-

65 ance slot intersecting said needle-throat

clearance slot between the ends of the latter,

and a thread-cutter movably mounted be-

70 low the work-clamp to operate on the under

side of the work through said thread-cutter clearance slot.

14. A sewing machine having stitch-forming mechanism including a reciprocating needle, work-supporting means having a 70 needle-hole and a thread-cutter clearance aperture spaced from the needle-hole and over which the thread to be cut is positioned by shifting the work subsequent to sewing, a thread-cutter mounted below the work-sup- 75 port and comprising a cutting blade disposed in a plane transverse to the plane of the work, and means for moving said blade to cause its point to graze the under surface of the work exposed by said clearance aperture 80 and pass between such surface and the thread leading from the needle-hole to the last stitch.

15. A buttonhole sewing machine comprising, stitch-forming mechanism including a 85 reciprocating needle and complementary loop-taking means, a work-clamp, means for relatively moving the stitch-forming mechanism and work-clamp to sew around a buttonhole, a scissors thread-cutter mounted below the 90 work-clamp with its blades in planes transverse to the plane of the work, and the direction of length of the buttonhole, and means for operating said thread-cutter.

16. A sewing machine having stitch-form- 95 ing mechanism including a reciprocating needle, a needle-throat, a work-clamp includ- ing upper and lower clamping means, means for relatively moving the stitch-forming mechanism and work-clamp to sew a group 100 of stitches and to relatively separate the latter and the stitch-forming mechanism sub- sequent to sewing to draw out a length of thread from the needle-throat, and thread- cutting means disposed below the plane of 105 the work and adapted to sever said thread length close to the last stitch while the work- clamp remains closed and in control of the work.

17. A sewing machine having, a frame, 110 stitch-forming mechanism including a recip-rocating needle, a needle-throat, a work- clamp including upper and lower clamping means, means for relatively moving the stitch-forming mechanism and work-clamp 115 to sew a group of stitches and to relatively separate the latter and the stitch-forming mechanism subsequent to sewing to draw out a length of thread from the needle-throat, said lower clamping means being apertured 120 to expose a portion of the under surface of the work and said length of thread, and thread-cutting means mounted on the ma- chine frame independently of the work-hold- er and adapted to sever said exposed thread 125 length close to the last stitch.

18. A buttonhole sewing machine having, in combination, stitch-forming devices includ- ing a needle, loop-taker mechanism, a 130 needle-throat, and a turret carrying the loop-

- taker mechanism and needle-throat, a work-holder means for relatively moving the stitch-forming mechanism and work-holder subsequent to the sewing operation to space 5 the stitched buttonhole from the needle-throat and position the sewing threads leading from the last stitch to the needle-throat horizontally against the under surface of the work, a scissors thread-cutter disposed at the 10 same side of the work as the turret and including blades disposed transverse to the plane of the work, one of the blades of said scissors being pointed and adapted to enter between the sewing thread and the work at 15 a point close to the last stitch, and means for projecting said scissors to cutting position and for closing them upon the sewing thread.
19. In a sewing machine, stitch-forming mechanism including a needle, a needle-throat, a work-holder including clamping feet occupying a position laterally spaced from the needle-throat after the sewing has been completed, and a thread-cutter including 20 a cutting blade disposed in a plane transversely of the plane of the work, said blade being pointed and adapted to enter between the under surface of the work and the thread leading from the needle-throat to the last 25 stitch.
20. In a sewing machine, stitch-forming mechanism including a needle, a needle-throat, a work-holder including clamping feet occupying a position laterally spaced 30 from the needle-throat after the sewing has been completed, and a scissors thread-cutter including blades disposed in planes transversely to the plane of the work, one of said blades being pointed and adapted to enter between the under surface of the work and the thread leading from the needle-throat to the last 35 stitch, and the other of said blades being disposed at the same side of the first mentioned blade as the last stitch.
21. A sewing machine having, in combination, stitch-forming mechanism including a needle, a turret, and loop-taking means mounted on the turret, a work-holder including lower work-supporting plates and 40 upper clamping feet, a buttonhole cutter, means for effecting a relative shift between the stitch-forming mechanism and work-holder subsequent to the sewing operation to afford clearance for the operation of 45 the buttonhole-cutter, and a thread-cutter mounted at the same side of the work as the turret and including a thread engaging blade operating in a plane transverse to the plane of the work-supporting plates and 50 between the sewing point and the cutting position of the buttonhole-cutter.
22. A buttonhole sewing machine having a frame comprising a bed and bracket-arm, 55 stitch-forming mechanism, a work-holder, means for relatively moving the stitch-form- 60
- ing mechanism and work-holder to sew around a buttonhole and to relatively separate the buttonhole and stitch-forming mechanism lengthwise of the machine-bed subsequent to sewing, thereby drawing out 65 a length of thread from the needle-throat, and a thread-cutter including a blade pivoted on an axis extending lengthwise of the machine-bed, said blade being adapted to sever said length of thread. 70
23. A sewing machine having, in combination, stitch-forming mechanism including a reciprocating needle and complemental loop-taking means mounted at opposite sides of the plane of the work, a thread-cutter carrying lever pivoted at the loop-taker side of the work on an axis transverse to and in substantially intersecting relation with a line normal to the plane of the work at the sewing point, and a thread-cutter including 75 a pointed blade mounted on said lever and adapted when said lever is swung on its pivot to enter between the under surface of the work and the thread leading from the last stitch to the sewing point, for severing 80 such thread.
24. A sewing machine having, in combination, stitch-forming mechanism including a reciprocating needle and complemental loop-taking means mounted at opposite sides of the plane of the work, a thread-cutter carrying lever pivoted at the loop-taker side of the work on an axis transverse to and in substantially intersecting relation with a line normal to the plane of the work at the 85 sewing point, and a thread-cutter including a scissors device mounted on said lever, one of the blades of said scissors device being adapted when said lever is swung on its pivot to enter between the under surface of the work and the thread leading from the last stitch to the sewing point, and means for closing said scissors device to sever the 90 thread.
25. A buttonhole sewing machine having, in combination, stitch-forming devices including needle and loop-taker mechanisms having a predetermined period of action, said loop-taker mechanism operating to retain a loop of needle-thread at the under 100 side of the work when the stitch-forming devices come to rest, a thread-cutter mounted below the work for travelling movement toward and away from the stitch-forming mechanism and adapted to sever both limbs 105 of such retaining loop, and means including a thread-engaging device movable with such thread-cutter toward and away from the stitch-forming mechanism for seizing such 110 loop and removing it from the field of action of the stitch-forming mechanism.
26. A buttonhole sewing machine having, in combination, stitch-forming devices including needle and loop-taker mechanisms having a predetermined period of action, 115

- 5 said loop-taker mechanism operating to retain a loop of needle-thread at the under side of the work when the stitch-forming devices come to rest, means for severing both limbs of such retained loop, and a thread-gripper having relatively separable jaws adapted to seize such loop and remove it from the field of action of the stitch-forming mechanism.
- 10 27. A buttonhole sewing machine having, in combination, stitch-forming devices including needle and loop-taker mechanisms having a predetermined period of action, said loop-taker mechanism operating to retain a loop of needle-thread when the stitch-forming devices come to rest, a thread-cutter below the work for severing both limbs of such retained loop, and a thread-gripper carried by said thread-cutter and operating to seize such loop and remove it from the field of action of the stitch-forming mechanism.
- 15 28. A buttonhole sewing machine having, in combination, stitch-forming devices including needle and loop-taker mechanisms having a predetermined period of action, said loop-taker mechanism operating to retain a loop of needle-thread when the stitch-forming devices come to rest, means for severing both limbs of such retained loop, a thread-gripper having separable jaws adapted to seize such loop and remove it from the field of action of the stitch-forming mechanism, a buttonhole-cutter, and connections between said buttonhole-cutter and the gripper for actuating the latter.
- 20 29. A buttonhole sewing machine having, in combination, stitch-forming devices, including needle and loop-taker mechanisms, a stop-motion, said loop-taker mechanism operating to retain a loop of needle-thread when the stitch-forming mechanism comes to rest, means for severing both limbs of the retained needle-loop, a gripper including a spring-pressed jaw for seizing said loop for removal from the field of action of the stitch-forming mechanism, a latch for holding said jaw open, and means for tripping said latch when the gripper is in loop-seizing position.
- 25 30. A buttonhole sewing machine having, in combination, stitch-forming devices, including needle and loop-taker mechanisms, a stop-motion, said loop-taker mechanism operating to retain a loop of needle-thread when the stitch-forming mechanism comes to rest, a buttonhole-cutter, means for severing both limbs of the retained needle-loop, a gripper including a spring-pressed jaw for seizing said loop for removal from the field of action of the stitch-forming mechanism, a latch for holding said jaw open, and means on the buttonhole-cutter for tripping said latch.
- 35 31. A buttonhole sewing machine having, in combination, stitch-forming devices, including needle and loop-taker mechanisms, a stop-motion, said loop-taker mechanism operating to retain a loop of needle-thread when the stitch-forming mechanism comes to rest, means for severing both limbs of the retained needle-loop, a gripper for seizing the severed loop, a latch for holding said gripper open, means for moving the gripper toward and away from the stitch-forming mechanism, means for tripping said latch when the gripper is in loop-seizing position, and a stop in the path of retracting movement of said gripper for opening said gripper to release the severed loop.
- 40 32. A buttonhole sewing machine having, in combination, a work-holder, stitch-forming devices including upper thread mechanism, under thread mechanism, and a turret on which the under thread mechanism is mounted, a needle-throat mounted on said turret and adapted to guide a stay-cord to the stitch-forming mechanism, means adapted at the end of the sewing operation to sever the cord between the needle-throat and the work, and means for arresting the feed of the cord during the formation of the initial stitches of the buttonhole, said means being timed to release the cord when the end thereof is substantially even with the initial stitches.
- 45 33. A buttonhole sewing machine having, in combination, stitch-forming mechanism, a work-holder, a feed-wheel, a stay cord guide adjacent the stitch-forming mechanism, means for arresting the feed of the cord during the formation of the initial stitches, and means for severing the cord between said guide and the work subsequent to sewing.
- 50 34. A buttonhole sewing machine having, in combination, stitch-forming mechanism, a work-holder, a feed-wheel and connections with the stitch-forming mechanism through which the feed-wheel is driven during the sewing to space the stitches around the buttonhole, a stay cord guide adjacent the stitch-forming mechanism, means for severing the stay cord between said guide and the work subsequent to sewing, and a stay cord nipper connected to the feed-wheel for arresting the feed of the cord during the formation of the initial stitches.
- 55 35. A buttonhole sewing machine having, in combination, a work-holder, stitch-forming mechanism including upper thread mechanism, under thread mechanism, and a turret on which the under thread mechanism is mounted, a needle-throat mounted on said turret and formed with a stay cord delivery aperture, means acting at the end of the sewing operation to sever the cord between the needle-throat and the work, and

- a cord check mounted on the needle-throat adjacent the cord delivery aperture for preventing accidental unthreading of the cord from such aperture.
- 5 36. A buttonhole sewing machine having, in combination, stitch-forming mechanism, a work-holder, means for relatively moving them to sew around a buttonhole, buttonhole cutting mechanism, and thread-cutting mechanism separate from and connected to
- be operated by the buttonhole cutting mechanism.
37. In a buttonhole sewing machine, buttonhole cutting means and thread-cutting means movable in different directions, and 15 a connection between said means for securing their simultaneous operation.
- In testimony whereof, I have signed my name to this specification.

EDWARD B. ALLEN.
